UNITED STATES PATENT OFFICE

YUKIO BUMA, OF NEW YORK, N. Y.

DESIGN FOR A CASSEROLE DISH

Application filed October 17, 1931. Serial No. 41,416. Term of patent 7 years.

To all whom it may concern:

Be it known that I, YUKIO BUMA, a subject of the Emperor of Japan, and a resident of the city of New York, county of New York, and State of New York, have invented a new, original, and ornamental Design for Casserole Dish, of which the following is a specification, reference being had to the accompanying drawings, forming part hereof.

In the drawings,

I claim:

The ornamental design for a casserole dish, as shown.

YUKIO BUMA.
